UNITED STATES PATENT OFFICE

FREDERICK E. REINHOLD, OF LOS ANGELES, CALIFORNIA

PADLOCK

Application filed June 6, 1932. Serial No. 615,570.

This invention relates generally to locks, more specifically to that form of locks commonly known as padlocks.

The principal object of the present invention is to provide a lock in which the shackle is removably secured to the body by screw threaded connections in lieu of the usual locking mechanisms.

Another object is to provide a locking device of strong and durable construction which is particularly adapted for use in locking electric meter boxes, gas valves or the like to cut off the service therethrough and which are to remain locked until the service is again restored.

Other objects and advantages will be apparent from the following description, reference being had to the accompanying drawing, in which:

Fig. 1 is a side elevation of the locking device, parts being broken away and shown in section.

Fig. 2 is a horizontal section taken substantially on line 2-2 of Fig. 1.

Fig. 3 is a section taken through the body of the lock.

Fig. 4 is a side elevation of the bow removed from the body.

Fig. 5 is a section taken through a modified form of the device.

Fig. 6 is a sectional view taken at right angles to Fig. 5 as indicated by line 6-6 of Fig. 5.

Fig. 7 is a perspective view of the device shown in Fig. 6 with the bow in open or unlocked position.

Fig. 8 is a side elevation of the locking plug of the device.

Fig. 9 is a plan view of the plug.

Fig. 10 is a perspective view of the wrench or key employed to manipulate the plug.

Referring more specifically to the drawing, 10 generally designates the improved locking device which consists of a body 12, a shackle 14, and a screw threaded plug 16, the latter serving to hold the shackle in locked engagement with the body.

Body 12 is preferably of cylindrical shape, having a screw threaded bore 18 therein, and formed in its upper portion are oppositely

disposed recesses 20 which communicate with openings 21 formed in the end wall 22 of the body.

The recesses 20 are provided to receive and center the free ends 24 of the shackle in order that the threads 25 thereon will properly register with threads 18, the shackle being secured to or held in locked engagement with the body through meshing of the threads 16a of the plug with threads 25 of said shackle as clearly shown in Fig. 1.

Plug 16 is provided with a head 16b that is adapted to be engaged by a socket wrench designated at 28 (see Fig. 10) for turning the same while applying or removing the shackle from the body. In the present instance head 16b of the plug is of annular shape having a flattened portion 16c. Wrench 28 is provided with a socket 30 secured to or formed integral with a stem 31 provided with a handle 32, the socket having an internal face 33 corresponding to the shape of head of plug 16.

When the device is in locked position the head of plug 16 is beyond the end face and entirely within the body, hence it cannot be removed except by application of the wrench. In other words, it would then be practically impossible to remove it with tools other than the wrench. Also the top wall 22 of the body protects the plug against such removal.

Each arm of the shackle is preferably provided with a lateral flange 34 having tapered upper face 35 which serves to prevent water entering the body during stormy weather.

It will be obvious that the shackle may be secured to or released from the body by screwing the plug into or out of engagement with the threads 25 on said shackle. It will be understood that it is not necessary to completely remove the plug to permit disengagement of the shackle with the body.

The modification shown in Figs. 5 and 6 consists of a body 40 and a shackle 41 slidably and pivotally connected thereto in a manner hereafter described.

Body 40 is internally threaded as indicated at 42 for the reception of a screw threaded plug 44 of the same shape as plug 16.

Formed in the body is a recess 45 and a bore

46, which respectively receive the threaded end 47 and arm 48 of the shackle.

The shackle is held in permanent engagement with the body, i. e. so that it cannot be come accidentally lost, by a collar or abutment 49 formed on the lower end of arm 48. This abutment contacts with a shoulder 50 formed at the juncture of bore 47 and the opening 51 formed in the top wall 52 of the body should the bow be raised or the device turned up side down when unlocked.

It will be understood that the collar or abutment is secured to or formed on the end of arm 48 after the same has been inserted into the bore 46.

When in locked position as shown the threads on plug 44 engage threads 47 of the shackle as shown in Fig. 5.

By unscrewing the plug to a position below threads 47 with the wrench, as shown in Fig. 10, the device may be unlocked. When thus released the shackle may be raised and swung to one side as shown in Fig. 7.

From the foregoing it will be seen that the locking device may be employed in the same manner as the usual padlock, is of simple construction and may be easily and cheaply produced.

I claim:

30 1. A padlock comprising a housing having a screw threaded bore therein, a bow shaped shackle having threaded ends movably mounted in said housing, and a screw plug mounted in the housing bore and engaging the threads of the shackle to lock the same to the housing.

40 2. A padlock comprising a cylindrical body having a screw threaded bore formed therein, a shackle having screw threads formed on the inner faces of its free ends extending into said body and a screw threaded locking plug having a deformed head and engaging the threads of the bore in said body and meshing with the threads on the free ends of said shackle, the head of said plug adapted to be engaged by a socketed member having an inner face of substantially the same shape as said head whereby the plug may be disengaged from the threads on said shackle, the head of said plug being beyond the end face and entirely within the body when in locked engagement with the shackle to prevent unauthorized removal.

50 3. A padlock comprising a cylindrical body having a screw threaded bore formed therein and oppositely disposed recesses communicating with the bore, a shackle having screw threads formed on the inner faces of its free ends extending into the recesses formed in said body, and a screw threaded locking plug having a deformed head and engaging the threads of the bore in said body and meshing with the threads on the free ends of said shackle, the head of said plug adapted to be

engaged by a socketed member having an inner face of substantially the same shape as said head whereby the plug may be disengaged from the threads on said shackle, the head of said plug being beyond the end face and entirely within the body when in locked engagement with the shackle to prevent unauthorized removal.

In testimony whereof I affix my signature.

FREDERICK E. REINHOLD.
